United States Patent Office

Des. 222,939
Patented Feb. 8, 1972

222,939

OIL CONTAINER

Robert V. Haas, Colonia, N.J., assignor to The Singer
Company, New York, N.Y.

Filed Oct. 21, 1970, Ser. No. 25,584

Term of patent 14 years

Int. Cl. D23—01

U.S. Cl. D23—5

Fig. 1

Fig. 2

Fig. 3

Fig. 4

Fig. 5

Fig. 6

Fig. 7

FIG. 1 is a front perspective view of an oil container, showing my design;

FIG. 2 is a rear perspective view thereof;

FIG. 3 is a top plan view thereof;

FIG. 4 is a front elevational view thereof;

FIG. 5 is a side elevational view thereof;

FIG. 6 is a rear elevational view thereof; and

FIG. 7 is a bottom plan view thereof.

I claim:

The ornamental design for an oil container, substantially as shown.
